VIBRATORY SOAP DISPENSER

Eduardo Alonso Planas, Habana, Cuba

Application March 9, 1945, Serial No. 581,861

3 Claims. (Cl. 222—161)

1

This invention relates to new and useful improvements in a soap dispenser.

More specifically, the present invention proposes the construction of a soap dispenser for dispensing liquid soap adapted to operate by vibration of the dispenser.

Still further, it is proposed to provide a dispenser as aforesaid having means for holding an inverted bottle of liquid soap in such a manner that one end of the bottle can be vibrated to cause a discharge of liquid soap from the vibrated end of the bottle, this latter end having an ejection nozzle.

A further object is to provide a dispenser as aforesaid in which the bottom or discharge end of the liquid soap bottle is loosely held, permitting vibrating, but is retained for limited vibratory movement only.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a liquid soap vibratory dispenser constructed in accordance with this invention.

Fig. 2 is a central sectional view of the dispenser of Fig. 1, vibratory positions of parts of the dispenser being indicated in dot-dash lines.

Fig. 3 is a central enlarged sectional view through a nozzle of the dispenser.

Fig. 4 is an enlarged perspective view of a bottle support forming part of the dispenser.

Fig. 5 is an enlarged perspective view of a bottle cap.

Fig. 6 is an enlarged perspective view of a bracket of the dispenser.

Fig. 7 is an enlarged reverse section on the line 7—7 of Fig. 2.

The liquid soap vibratory dispenser, according to this invention, comprises a support 10 adapted to be secured to a wall, door or other similar location at the place where it is desired to dispense the soap, such as in a lavatory, bathroom or kitchen. Support 10 includes a rectangular plate 11, which may be of metal, wood, plastic, tile or other suitable material, and two cross pieces 12 held to the plate 11 by screws 13 forming the means for connecting the support 10 to the aforesaid wall. Plate 11 is made quite thin, adapting it to vibrate between the screws 13, the cross pieces 12 holding the plate 11 away from the aforesaid wall so that it is free to vibrate.

2

Two brackets are secured to the support 10, the top bracket 14 having a large eye 15 and the bottom bracket 16 having a smaller eye 17. Each bracket is made of a strip of metal bent to provide the eye and extending therefrom two legs 18 ending in feet 19 secured to the plate 11 by screws 20. The legs 18 are connected adjacent the eye by a bolt 21. These brackets are made of thin metal adapted to vibrate.

10 A nozzle 22 having a cylindrical wall 23 is secured, as by soldering, in the eye 17. The nozzle 22 is open at the top and is closed at the bottom by a two-ply wall 24 having a conical jet orifice 25. A bottle support 26 is supported on the nozzle 15, 22 by a flange 27 of the support which rests on the top edge of the bracket 16 and nozzle 22. This bottle support has a neck 28 of smaller outside diameter than the inside diameter of the nozzle, the neck 28 being disposed loosely in the nozzle.

15 20 The liquid soap is disposed in a bottle 29, preferably of glass, set upside down in the dispenser and forming a part thereof. The bottle 29 is of the usual type having a small top or neck 30 externally threaded. This neck is adapted to fit fairly

25 snugly in the support 26. A cap 31 is threaded on the neck of the bottle closing the bottle. Cap 31 has a jet orifice 32. In assembling the bottle 15, 30 in the dispenser, it is first filled with liquid soap only to an extent such that a certain amount of

30 air will be at the upper end of the bottle when it is inverted in the dispenser. Then the support 26 is put over the bottle neck and the cap 31 screwed thereon. The outside diameter of the bottle support 26 is smaller than the inside diameter of the eye of the top bracket so that it will slide

35 therethrough, permitting assemblage of the bottle with the support connected thereto with the dispenser.

The eye 17 of the bottom bracket 16 is provided with a tab 33 connected to the outside face of the eye by screws 34. This tab provides means for vibrating the dispenser.

The operation of the dispenser is as follows: Assuming the bottle is in the dispenser and that there is an air space in the bottle above the liquid soap therein, all that is necessary in order to cause the dispenser to discharge liquid soap, is to touch the tab 33 and jar it sufficiently to cause the bottom bracket to vibrate. This causes vibration of other parts of the dispenser. For instance, the support 10 may vibrate and the upper bracket may vibrate. However, the main vibration will be of the lower bracket and especially of the nozzle 22.

55 The lower bracket vibrating, the bottle is vibrated, agitating the liquid soap and causing a

small amount to be discharged either as drops of liquid or as foam through the jet orifice 32 of the cap and then through the jet orifice 25 of the nozzle. This vibration may be extended by repeated jarring of the tab 33 until the desired amount of liquid soap has been discharged. When the device is at rest that is to say, when it is not being vibrated, the liquid cannot escape from the bottle due to the fact that the nozzle jet of the cap is small and no air can slip through to release the liquid, the air only being able to pass when the liquid is being agitated.

From the foregoing description it will be seen that the dispenser of the present invention has no working parts which can wear out, become clogged with soap or become loose. Furthermore, it is always ready for use. It also may be made of available and economical materials.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A liquid soap dispenser adapted to dispense soap in response to vibration of said dispenser comprising a pair of vertically spaced brackets, each of thin metal construction adapted to vibrate, each bracket having an eye, the eye of the top bracket being in line with and larger than the eye of the bottom bracket, a nozzle secured in said bottom bracket eye and having an ejection orifice, a bottle for containing liquid soap, said bottle having a reduced neck, a bottle support mounted on said bottom bracket eye having a reduced neck extending in said nozzle, said support neck having an outside diameter less than the inside diameter of said nozzle and having a central bore, said bottle being mounted in inverted position with its neck fitting closely in said bore, a cap secured on said bottle neck having an ejection orifice in line with said nozzle orifice, whereby by shaking said bottom bracket to vibrate said dispenser, the liquid soap in said bottle will be agitated, causing the discharge of some of said liquid through said ejection orifices, and a tab on the eye of said bottom bracket for use in manually causing said vibrations.

2. A liquid soap dispenser adapted to dispense soap in response to vibration of said dispenser comprising a thin supporting plate having its upper and lower ends provided with means for securing said plate in spaced relation to a wall, thereby permitting said plate to flex between its ends, a pair of vertically spaced brackets attached to said supporting plate between the ends thereof, each bracket having an eye, the eye of the top bracket being in line with and larger than

the eye of the bottom bracket, a nozzle secured in said bottom bracket eye and having an ejection orifice, a bottle for containing liquid soap, said bottle having a reduced neck, a bottle support mounted on said bottom bracket eye having a reduced neck extending in said nozzle, said support neck having an outside diameter less than the inside diameter of said nozzle and having a central bore, said bottle being mounted in inverted position in said eyes with its neck extending through said bore, and a cap secured on said bottle neck having an ejection orifice in line with said nozzle orifice, whereby by shaking said bottom bracket to vibrate said dispenser, the liquid soap in said bottle will be agitated, causing the ejection of some of said liquid through said ejection orifices, and a tab secured to said bottom bracket for use in vibrating said dispenser.

3. A liquid soap dispenser adapted to dispense soap in response to vibration of said dispenser comprising a thin supporting plate having its upper and lower ends provided with means for securing said plate in spaced relation to a wall, thereby permitting said plate to flex between its ends, a pair of vertically spaced brackets, each bracket having an eye and two legs, said legs being united adjacent said eye and diverging horizontally outwardly therefrom and being attached with their spaced ends to said supporting plate, the eye of the top bracket being in line with and larger than the eye of the bottom bracket, a nozzle secured in said bottom bracket eye and having an ejection orifice, a bottle for containing liquid soap, said bottle having a reduced neck, a bottle support mounted on said bottom bracket eye having a reduced neck extending in said nozzle, said support neck having an outside diameter less than the inside diameter of said nozzle and having a central bore, said bottle being mounted in inverted position with its neck extending through said bore, a cap secured on said bottle neck having an ejection orifice in line with said nozzle orifice, whereby by shaking said bottom bracket to vibrate said dispenser, the liquid soap in said bottle will be agitated, causing the ejection of some of said liquid through said ejection orifices.
